UNITED STATES PATENT OFFICE

CHARLES W. WERST, OF PHILADELPHIA, PENNSYLVANIA, AND ELMER E. HICKEN, OF COLLINGSWOOD, NEW JERSEY

TENDER FRAME

Application filed April 17, 1930. Serial No. 445,040.

Our invention relates to certain improvements in the frames of tenders for locomotives and like rolling stock.

One object of our invention is to make the frame of rolled steel shapes, which are welded together to form a unitary structure.

A further object of the invention is to make the longitudinal members of the frame continuous throughout and to notch and slot 10 the cross members for the reception of the longitudinal members.

In the accompanying drawings:

Fig. 1 is a plan view of our improved frame for the tender of locomotives;

Fig. 2 is a side view;

Fig. 3 is a longitudinal sectional view on the line 3—3, Fig. 1;

Fig. 4 is a sectional view on the line 4—4, Fig. 1;

Fig. 5 is an enlarged sectional view of part of Fig. 3;

Figs. 6 and 7 are enlarged views of part of Fig. 4;

Fig. 8 is a detached perspective view of 25 one of the longitudinal stringers;

Fig. 9 is a detached perspective view of one of the cross members; and

Fig. 10 is a section through the rear draft casting.

The frame of the tender consists of four longitudinal members. Each of these members is in the form of a channel beam. The outside members 1—1 form the outer longitudinal stringers of the frame, while the

members 2—2 form the inner longitudinal members and are arranged comparatively close together, one on each side of the longitudinal center of the frame and resist the end thrusts of the bumpers. 3 are the trans-

verse members, which in the present instance are wide flanged I-beams, as shown in Fig.

5. It will be noticed, referring to the drawings, that the transverse I-beams are of greater height than the longitudinal chan-

nelled stringers. By making the transverse I-beams of greater depth than the longitudinal channel members, the transverse beams can be slotted, as at 4, Fig. 9, for the passage of the channel members 2 and

50 can be notched and shaped at the ends as at

5, Fig. 9, to the form of the outside channel members 1. This is clearly shown in Figs. 4, 6 and 9.

When the parts are assembled, then the longitudinal members are welded on the lines *x*, Fig. 7, to the transverse members, and the side members 1 are welded to the ends of the web of the said transverse members at *y*—*y*, and to the upper and lower flanges of the members at *z*—*z*, Fig. 6. 60

6 is the forward bumper, which is in the form of a casting, as shown in Figs. 1, 2 and 3, and back of this bumper is the draw head 7 which is another casting, the two castings being secured to the longitudinal members by welding at the points indicated. 8 is the rear bumper casting, which is welded to the ends of the longitudinal members. 11 is a draft casting in which is a yoke 12. Within the yoke is the coupler 13 and a 70 friction draft gear of any suitable type. It will be noticed in referring to Fig. 10, which is a cross sectional view of the two longitudinal beams 2—2 and the draft casting, that the draft casting 11 has flanges 14 75 which overlap the top of the beams 2 and flanges 15 which underlap said beams. The upper flanges are preferably welded to the beams at 16. By flanging the draft casting the shear strain is taken off of the weld. 80

At each end of the tender are plates 9, which overlap the bumpers and cover the portions of the ends of the beams, as shown in Figs. 1 and 3.

Secured to two of the transverse members 85 are the center plates 10 of the frame. Side bearings, which are made as a steel casting and U-shaped in cross section, may be secured to the underside of the transverse members, to which the center bearings are 90 attached, as shown in Fig. 4.

By the above construction it will be seen that a very substantial tender frame is made without the use of bolts or rivets in securing 95 the longitudinal members to the transverse members, and that by proportioning the members in the manner shown, the longitudinal members which form the stringers can be made in a single piece, extending 100

from a bumper at one end of the frame to a bumper at the opposite end thereof.

While we have described our invention as particularly adapted for frames of tenders of locomotives, it will be understood that the invention can be used on frames of tank cars and like rolling stock.

We claim:

1. The combination in a frame for a tender of a locomotive, consisting of two series of rolled members, one series extending longitudinally and continuously throughout the length of the frame, and the other series extending transversely, and being slotted 15 for the passage of the longitudinal members, which are located intermediate of the sides of the frame, and notched at each end to fit against the side longitudinal members.

2. The combination in a tender frame for 20 a locomotive, of two series of longitudinal members extending substantially from one end of the frame to the other; bumpers secured to the ends of said members; and a series of transverse members of greater height 25 than the longitudinal members, said transverse members being I-beams, the webs of said beams being slotted for the passage of the inner series of longitudinal members and being shaped at the ends to fit against outer longitudinal members.

3. The combination in a tender frame for 30 a locomotive, of two series of longitudinal members extending substantially from one end of the frame to the other; bumpers secured to the ends of said members; and a series of transverse members of greater height than the longitudinal members, said transverse members being I-beams, the webs of said beams being slotted for the passage 35 of the inner series of longitudinal members and being shaped at the ends to fit against outer longitudinal members; a draw head casting at one end of the frame and located directly back of the bumper at that end of 40 said frame and secured to the bumper and the inner longitudinal members of the frame.

4. A frame for a tender or the like, of a 45 series of longitudinal members extending substantially the full length of the frame and three transverse members of greater height than the longitudinal members; bumpers at each end of the frame, said longitudinal members extending through the transverse members and secured to said 55 transverse members and bumpers by welding, two of said transverse members having center plates secured thereto.

5. The combination in a tender frame, of 60 an inner and an outer series of longitudinal members, said inner longitudinal members being spaced apart; a bumper; a draft casting extending between the longitudinal members and having flanges at each side, the upper flanges extending over the upper edge 65 of the inner longitudinal members and the

lower flanges extending under the said longitudinal members.

6. The combination in a locomotive tender frame, of two sets of longitudinal members, the inner sets being spaced apart and the outer members being at the outer edge of the frame; a bumper at each end of the frame welded to the longitudinal members; a draw head casting at the forward end of the frame and located directly back of the bumper, 70 said draw head casting being welded to the longitudinal members; a draft casting located between the two inner longitudinal members and welded thereto; a series of transverse members through which the inner 75 longitudinal members extend.
